UNITED STATES PATENT OFFICE.

WILLIAM I. CALLAWAY, OF ATLANTA, GEORGIA.

GRINDING-MACHINE.

1,230,111.

Specification of Letters Patent. Patented June 19, 1917.

Application filed October 8, 1916. Serial No. 123,537.

To all whom it may concern:

Be it known that I, WILLIAM I. CALLAWAY, a citizen of the United States, residing at Atlanta, in the county of Fulton and State of Georgia, have invented new and useful Improvements in Grinding-Machines, of which the following is a specification.

This invention generically relates to an improved machine for grinding circular saws and cutters of various types, but it more specifically comprehends a machine for grinding milling cutters or other tools having cutting surfaces regularly spaced on a circle.

Many efforts have been made in the past, but with varied success, to construct machines for sharpening circular saws, milling cutters and the like, where it is essential that the longitudinal depth in alinement with the axis, and the lateral face of the tooth, be ground correspondingly, and accurately.

Heretofore, machines designed to accomplish the aforementioned results have comprised such intricate mechanism and multiplicity of parts as to render their efficiency incommensurate with the high cost of production.

One object of my invention is to provide a machine for accurately grinding off a predetermined amount from the cutting edge or lateral face of the tooth, and from the throat or longitudinal depth toward the center, so that all the teeth may be ground uniformly, and after successive grindings, if it is desired, be the same length as originally.

To accomplish this, I have provided gaging means which will permit exactly the same amount to be ground off the lateral face of the tooth and from the throat thereof, or more or less from either, as the type of cutter to be ground may require.

The predetermined amount taken from the lateral face and from the throat of the tooth is effected by a single and continuous act of grinding, and to grind all of the teeth successively, but a single setting or adjustment of the gaging means is necessary.

A further object of this invention is to provide a machine simple in construction, comprising few parts, and not only efficient for the purpose already enumerated but also capable of utilization in sharpening straight edge tools, thereby effecting a plurality of uses in a single structure.

With these and other objects in view, my invention consists in certain novel details of

construction, combination and arrangement of parts to be more particularly hereinafter set forth and claimed.

In the accompanying drawings in which 60 corresponding parts are indicated by similar reference characters:—

Figure 1 is a perspective view of my improved grinding machine.

Fig. 2 is a rear elevation thereof.

Fig. 3 is a perspective view, with the cutter carrier at an angle, and operatively positioning a straight edge tool.

Fig. 4 is a central vertical section with parts shown in elevation.

Fig. 5 is a vertical section taken on the line 5—5 of Fig. 4.

Fig. 6 is a fragmentary plan view, showing the grinding wheel as completing the grinding of one of the cutter teeth.

Fig. 7 is a similar view with the succeeding tooth operatively positioned for grinding; and

Fig. 8 is a vertical section taken on the line 8—8 of Fig. 1 in the direction of the arrows.

In the illustrated embodiment characterizing this invention, there is shown a base or supporting frame 1 having a pair of properly spaced vertical standards 1', provided at 85 their upper extremities with bearings 2, journaling an arbor 3 intermediate the length of which is a pulley 4, for obvious purposes. On one end of arbor 3 is an emery wheel 5 or other similar grinding element, 90 depending upon the character of the tool to be ground.

Integral with one of the vertical standards is a rearwardly extending arm 6, to the free end of which is swivelly affixed a frame or 95 bed plate 7 supporting a compound slide comprising an auxiliary carriage 8 movable longitudinally of bed 7, and tool carrier 9 slidably positioned on carriage 8 and operable transversely of the bed 7, the tool carrier 9 thus being capable of both transverse and longitudinal adjustment relative to the rotary axis of emery wheel 5.

Depending from the extremities of bed 7, are the centrally apertured ears 10 and 12, 105 respectively. The opening of the former alines with an opening in the end of arm 6 for the passage of a bolt 11, affording the swivel connection hereinbefore mentioned; while that of the other accommodates a 110 screw 13, retained in position by collar 14 and cap 15, for a purpose hereinafter to be

stated. Projecting through suitably aligned openings in cap plate 15 is an L shaped rod 16 for actuation of screw 13, though of course, other means may be employed if more 5 desirable.

The bed 7 has extending substantially throughout its length a longitudinal slot 17, and contiguous its longitudinal edges vertical walls 18, to which are attached guide plates 19, forming channels 20.

Auxiliary carriage 8 is constructed with shoulders 21, slideable over guide plates 19, and a depending inverted T-shaped portion 22, the latter forming longitudinal flanges 22' adapted to project within channels 20. Extending downwardly central of portion 22, is a lug 23, having therethrough an internally threaded opening to receive screw 13, the rotation of which imparts longitudinal movement to said auxiliary carriage, 10 as will be readily understood without further description.

This auxiliary carriage 8 has contiguous its transversely extending edges, vertical walls 24, and secured to said walls guide plates 25, forming channels 26 into which the longitudinal edges of tool-carrier 9 project, the latter having situated thereon, saw, circular cutter, or other tool to be sharpened as 20 will be more fully hereinafter described.

The tool-carrier 9 comprises a rectangular bed or plate, chamfered adjacent its upper longitudinal edges to effect shoulders 9', which abut the edges of guide plates 25 and 35 insure uniform rectilinear movement of the carriage. Contiguous one end of carrier 9, is a cylindrical standard 29, adapted to function as a mounting for the circular cutter 27, having the usual opening 28. On the 40 upper externally threaded end of standard 29 is positioned nut 30, holding in position a part of the gaging mechanism hereinafter to be mentioned, said nut having therein diametrically opposed openings to facilitate its 45 removal.

In order to enable uniform grinding of the cutter teeth, a gaging mechanism is employed, by means of which, a step by step circular movement of the cutter is obtained, 50 each step advancing the respective cutter through a sector of their circle of movement, defined by the distance between their cutting surfaces. This gaging mechanism comprises, a cylinder or collar 31, encircling standard 29, and held against vertical movement thereon by nut 30 previously mentioned. This collar 31 is reduced adjacent its lower end, effecting shoulder 32, to abut the upper surface of the cutter, the reduced 55 portion fitting between standard 29 and the surrounding wall of opening 28, so as to function as a bushing and consequently eliminate any possibility of eccentric collar movement. A key 33, extending laterally 60 from collar 31 at a point thereon immedi-

ately below shoulder 32, engages a keyway 28', formed in the wall of cutter opening 28. This arrangement interlocks collar 31 and cutter 28 so that the same may be simultaneously rotated.

Integral with and surrounding collar 31, is a laterally extending flange 34, having therethrough a number of perforations 35, regularly spaced on a plurality of circles concentric with the rotary axis of said cutter. To obtain the circumferential advancement of the cutter teeth in the manner hereinbefore described, the openings 35, are situated in alinement with the cutting surfaces of the tool operated on, hence their spacing 70 is directly proportional to the width of the cutter teeth. Although in the illustration the inner circle of openings 35, is shown as applicable to the particular cutter being ground, selection of a suitable circle is determined by the dimension of the cutter.

Constituting a part of the gaging mechanism and coacting with the apertured flange 34, is a vertically movable spring-pressed plunger or dog, whereby the selected cutter-tooth may be rigidly maintained relative to the grinding wheel, said plunger being mounted in the following manner: Central of carrier 9, there is disposed an annular upright 31, having concentric with its upper end an externally threaded shank 37, upon which is positioned a winged thumb screw 38, to engage the flattened extremity of a substantially S-shaped arm 39, said extremity being slotted as at 40 to permit passage of shank 37, whereupon to enable longitudinal movement of the arm. The other extremity of arm 39, is formed with an annular enlargement 41, having an opening 42, through which passes the stem of plunger 100 or dog 43. Opening 42 is enlarged to afford a seat for the helical spring 44, positioned on said stem, with its lower end abutting flange 45, carried by the latter immediately above the tapered head thereof. That portion of the plunger extending through and above the top of cylinder 41, is externally threaded to receive thumb screw 46, which not only acts as a means for retaining said plunger in position, but also for retracting 110 the same when necessary. From the above it is apparent, after the desired opening 35, has been brought to proper position, and the plunger head seated therein the cutter will be firmly held against rotary movement.

On the end of carrier 9, opposite that upon which is positioned the circular tool to be sharpened, is a means for holding straight-edge tools at any required angle, consisting of a rectangular plate 47, with beveled longitudinal edges 48, and formed with a centrally arranged opening 49, for the passage of bolts 50, which coöperate with the blades to be ground, and hold the same in position upon said plate. An end 120

piece 52, integral with the aforementioned extremity of carrier 9, is formed with an opening through which extends an externally threaded lug 52', carried by plate 47, 5 said lug being secured by a nut of usual construction.

To enable auxiliary carriage 8, or carrier 9, to be fixedly secured at any desired point in the path of their travel, set screws 53 10 and 54 are provided in connection with bed 7 and auxiliary carriage 8 respectively, as clearly shown in Figs. 1, 4, and 5.

As the gaging mechanism above referred to is directed entirely to lateral grinding, 15 that is to say, from front to rear of the cutter tooth, in order to secure indentity in treatment of the successive cutter teeth, it is necessary to predetermine the extent of grinding in the direction of the vertical axis 20 of the cutter, hence a stop 55 is in position upon carrier 9, with its side extensions 56, engaging the longitudinal edges of said carrier. A set screw extending through one of the side extensions 56, permits adjustment 25 of said stop depending on the exigency of the situation.

From the foregoing structural outline, it will be apparent, the operation of this machine is as follows: Assuming the parts assembled as in Fig. 1, the cutter carrier however being sufficiently retracted to permit rotation of the cutter, and further supposing the tooth therein shown in contact with the working face of the grinding wheel, to be 30 the initial or starting tooth, then to effect suitable grinding thereof, auxiliary carriage 8, and its incidental structure is actuated through the instrumentality of the mechanism hereinbefore described, causing the 35 circular cutter to travel in a plane parallel to the horizontal axis of the grinder, until the cutting surface of the initial tooth is situated in a plane spaced from that of the working face of said grinding wheel, a distance equal to the cut or grind to be removed, usually one or two-thousandths of 40 an inch, in which position it is fixed by set screws 53. Auxiliary carriage 8, being thus positioned, as carrier 9 is slowly advanced, 45 in a plane at right angles to the horizontal axis of the grinding wheel, the required material from the front to the rear of the tooth, as well as lengthwise thereof will be removed. When the maximum cutting length- 50 wise of the tooth has been effected, stop 55 is adjusted to abutting relation with respect to carriage 8, (see Fig. 5,) so that each tooth may be ground lengthwise to the same extent. After the initial or starting tooth 55 has been sufficiently ground, dog 43, of the 55 gaging mechanism, is withdrawn and placed in the next opening 35, of flange 34, whereupon the succeeding cutter tooth, is disposed with its cutting surface in a plane 60 spaced from the working face of the grind-

ing wheel, such spacing corresponding to the width of the material removed from the preceding tooth. The operation of advancing the carrier, as before described, being repeated, a cut or grind is accomplished identical to that of the first mentioned tooth. 70 This treatment being accorded successively to all of the cutter teeth, they will be ground with absolute uniformity and accuracy in both directions, that is, from front to rear 75 or laterally, and lengthwise or in the direction of their axis. In this connection, should it be deemed expedient in determining the amount of material to be removed from the starting tooth, one of the guide 80 rails 19, may be graduated in inches (not shown) and fractions thereof as will be readily understood without further discussion. In the event a straight edge tool is to be sharpened, the relative positions of the 85 circular cutter and the plate adapted to hold the straight edge tool are reversed, said tool being held at a suitable angle to the grinding wheel so that it may be ground in the usual manner. 90

In conclusion, it may be said, this device not only simplifies the machines heretofore designed for sharpening tools of the character specified, but also reduces the cost of such operation, by eliminating the skilled 95 labor ordinarily essential to the proper treatment of a milling tool.

I claim—

1. In a grinding machine, the combination with a rotary grinder, a cutter carrier 100 relatively movable with respect to the grinder, and capable of rotatably supporting a circular cutter; of a gaging mechanism coöperating with said cutter and governing its rotary movement, embodying an 105 annular member concomitantly revoluble and concentrically situated in a plane coincident with that of said cutter, said member having a circular series of regularly spaced openings, said spacing being proportional to that of the cutter teeth, and a reciprocatory plunger adapted to enter said openings, whereby to properly position the cutter teeth relative to the grinder, substantially as and for the purpose set forth. 110

2. In a grinding machine, the combination with a rotary grinder, a cutter carrier 120 relatively movable with respect to the grinder, and capable of rotatably supporting a circular cutter; of a gaging mechanism coöperating with said cutter and governing its rotary movement, embodying an annular member concomitantly revoluble and concentrically situated in a plane coincident with that of said cutter, said member having a circular series of regularly spaced openings, said spacing being proportional to that of the cutter teeth, and a spring pressed reciprocatory plunger adapted to enter said opening, whereby to opera- 125 130

tively position the cutter teeth relative to the grinder, substantially as and for the purpose set forth.

3. In a grinding machine, the combination with a rotary grinder, a cutter carrier movable transversely and longitudinally of the rotary axis of said grinder, and means in connection with said carrier to horizontally and rotatably support a circular cutter; of a gaging mechanism coöperating with the cutter and governing its rotary movement, embodying an annular member concomitantly revoluble and concentrically situated in a plane coincident with that of said cutter, said member having a circular series of regularly spaced openings, said spacing being proportional to that of the cutter teeth, and a vertically movable spring pressed plunger adapted to enter said openings to properly position the cutter teeth relative to the grinder, substantially as and for the purpose set forth.

4. In a grinding machine, the combination with a rotary grinder, a cutter carrier movable transversely and longitudinally with respect to the rotary axis of said grinder, and means in connection with said carrier to rotatably and horizontally support a circular cutter; of a gaging mechanism coöperating with the cutter to enable a step by step rotary movement thereof, embodying a sleeve keyed to and concentrically mounted upon the cutter, an annular flange surrounding the upper end of said sleeve, and having therein a circular series of regularly spaced openings, the spacing of said openings being proportional to that of the cutter teeth, and a vertically movable spring pressed plunger adapted to enter said openings, whereby to properly position the cutter teeth relative to the grinder, substantially as and for the purpose set forth.

5. In a grinding machine, the combination with a rotary grinder, a cutter carrier movable transversely and longitudinally

with respect to the rotary axis of said grinder, and a cutter carrying shaft situated upon said carrier in a plane at right angles thereto, and capable of rotatably supporting a circular cutter; of a gaging mechanism to enable a step by step rotation of the cutter, embodying a sleeve, circumscribing said shaft and having its lower end keyed to the cutter, an annular flange surrounding the upper end of said sleeve, and provided with a circular series of regular spaced openings, the spacing of said openings being proportional to that of the cutter teeth, and a vertically movable spring pressed plunger adapted to enter said openings, whereby to properly position the cutter teeth relative to the grinder, substantially as and for the purpose set forth.

6. In a grinding machine, the combination with a rotary grinder, a cutter carrier movable transversely and longitudinally of the rotary axis of said grinder, means to predetermine the extent of either carrier movement, when the latter is operable toward the grinder, and a cutter carrying shaft situated upon said carrier in a plane at right angles thereto, and capable of rotatably supporting a circular cutter; of a gaging mechanism to enable a step by step rotation of the cutter, and embodying a sleeve circumscribing said shaft and having one end keyed to the inner periphery of the cutter, an annular flange surrounding the upper end of said sleeve and provided with a circular series of regularly spaced openings, the spacing of the openings being proportional to that of the cutter teeth, and a vertically movable spring pressed plunger adapted to enter said openings, whereby to properly position the cutter teeth relative to the grinder, substantially as and for the purpose set forth.
